UNITED STATES PATENT OFFICE.

HENRY F. PARKER, OF BROOKLYN, NEW YORK, ASSIGNOR TO THE COAST PIGEON MANUFACTURING COMPANY, OF CUYAHOGA FALLS, OHIO.

DESIGN FOR A FLYING TARGET.

SPECIFICATION forming part of Design No. 26,912, dated April 13, 1897.

Application filed February 26, 1897. Serial No. 625,215. Term of patent 14 years.

To all whom it may concern:

Be it known that I, HENRY F. PARKER, a citizen of the United States, residing at Brooklyn, in the county of Kings and State of New York, have invented and produced a new and original Design for Flying Targets, of which the following is a specification, reference being had to the accompanying drawings, forming part thereof.

10 Figure 1 is a face view of a target showing the design, and Fig. 2 a cross-sectional view on the line $x-x$, Fig. 1, these two views being deemed necessary to fully illustrate the design.

15 The design applies to a saucer-shaped target of brittle composition for trap-shooting. The leading feature of the design consists in a convolute spiral rib continuing from the

center of the target outward toward the periphery, forming a closely-arranged series of 20 corrugations.

The coiled rib a winds from the center C to the smooth annulus B at the crown, and the coiled rib b winds from the annulus B to the surface of the rim A, where it merges into 25 said surface. The coils each thereby form continuous connecting-ribs between two diameters, giving ornament consistent with strength.

What I claim is—

30 The design for a flying target herein shown and described.

HENRY F. PARKER.
